MACHINE FOR FORMING BUCKLES ON
BALE TIES

Henry E. Werner, Houston, Tex., assignor, by direct and mesne assignments, to H-T Band Socket Corporation, Galveston, Tex., a corporation of Texas

Application March 5, 1937, Serial No. 129,110

13 Claims. (Cl. 140—73)

The invention relates to a bale tie buckle making machine and more particularly to a machine for forming a bale tie buckle as an integral part of the tie.

5 It is an object of the invention to provide a simple and economical machine that will form buckles on bale ties at a high rate of speed and insure uniformity in the finished product.

10 It is also an object to provide a bale tie and buckle forming machine wherein all steps in forming the buckle are performed automatically and the machine will operate at a high rate of speed and with a minimum of attention by the operator.

15 A further object is to provide a machine that will form a combination bale tie and buckle from a single piece of bale tie material.

20 A more specific object is to provide a machine that will automatically form a socket or buckle upon a tie member by wrapping the tie member about itself at one end thereof.

25 A further and particular object of the invention is to provide an automatic mechanism for carrying out the steps of improvements in the art of bale ties and holders described and claimed in Patent No. 1,969,109.

30 The invention will be more readily understood and other objects will be apparent from the following description taken in connection with the accompanying drawings, in which:

Figure 1 is a plan view of the device of the invention.

Figure 2 is an end elevation.

Figure 3 is a side elevation of the machine.

35 Figures 4 and 5 are sectional views taken on line 4—4 and line 5—5, respectively, in Figure 1.

Figures 6 to 9 are perspective views showing the successive operations performed upon a bale tie in forming the combination tie and buckle.

40 Fig. 10 is a sectional view taken on line 10—10 of Fig. 1.

Fig. 11 is an enlarged plan view of a portion of the device.

Fig. 12 is a sectional view taken on line 12—12 of Fig. 1.

45 In the manufacture of bale ties and buckles of the type for which the device of the invention is designed, a definite sequence of operations must be performed upon the tie material in order that the buckle may be formed integral therewith. The device of the invention performs these operations during a step-by-step movement of the tie through the machine, an essential operation being performed upon the tie during the successive intervals of rest.

The machine comprises essentially a conveyor mechanism designated as 1 and a metal forming head generally designated as 2, the latter of which sequentially performs the necessary operations upon the tie material as the tie is progressively moved by the conveyor.

5 The device will be best understood by reference first to the operations to be performed thereby, as is illustrated in Figs. 6 and 9. The tie and buckle stock 10 may be of sufficient length 10 to form a complete tie and buckle or the length thereof may be sufficient to form only the buckle with a short projecting end to which tie stock of any desired length may be secured as by welding or riveting. In either event the first operation 15 is that of folding the stock at 11 through an angle of 180 degrees so that the folded back portion is of sufficient length, with the end portion 12 of double thickness, as will form the tie buckle.

20 The second operation is that of bending end portion 12 to form a fold 13 at an angle of 45 degrees with the axis of the stock 10 and causing extension 14 to lie in the plane of stock 10 but with its axis at right angles thereto. Fold 13 is so positioned that end portion 15 of the 25 overlap is of sufficient length that a second fold 16 may be formed in the succeeding operation by reversely bending overlap portion 15 through an angle of 180 degrees, the bend taking place at such distance from edge 17 of extension 14 30 that fold 16 is displaced, as at 18, from edge 17 when the fold is completed. The final operation is illustrated in Fig. 9, which shows the buckle as completed by wrapping extension 14 in a counter-clockwise direction, as viewed from the 35 left in Fig. 8, about tie 10 and overlapping folds 19.

It should be noted that extension 14 is of such length that it passes entirely around stock 10 and terminates on the nether side of the stock, as seen in Fig. 9, on the second turn. Attention 40 is also directed to the fact that the superposed thicknesses of metal presented by this final wrapping operation are maintained in spaced relation with the nether surface of the tie to form a socket in the loop through which the opposite 45 end of the tie is passed when used for its intended purpose.

Referring to the figures of the drawings, showing the machine, 3 represents a composite frame having legs 4 and a bed 5, upon which the operating elements are mounted.

50 The conveyor 1 comprises a stub shaft 21 and a drive shaft 22, each of which extends longitudinally of frame 3 and is rotatably mounted in journal bearings 23 secured to bed 5. Pairs of 55

sprocket wheels 24, 25, mounted upon shafts 21, 22, carry conveyor chains 26, to which are secured carrier bars 27 at spaced intervals. Each 5 of these carrier bars is provided with a cam clamp 28 having a camming lever 29 to clamp and retain tie members 10 thereon during movement of the conveyor as the tie members 10 are carried through the machine upon conveyor 1, as is indicated by arrow 39.

10 The plate 5 overhangs the end of frame 3 at 40 and carries a drive shaft 41 provided with a driving pulley 42 and a drive pin 43. A stub shaft 44 is driven through gear 45 meshing with pinion 43 and drives a cam shaft 50 through 15 pinion and gear 51, 52.

Shaft 63 is driven from cam shaft 50 through bevel gears 60 and 61 and has affixed thereto the driving element of a Geneva drive generally designated as 62. By means of the driving mechanism just described intermittent rotary movement is imparted to shaft 22 whereby conveyor 1 is moved in a step-by-step manner to bring tie member 10 into successive positions for operations thereon, as hereafter described.

25 Mounted upon bed plate 5 is a plate 112 having a flange 113 (Fig. 1). This plate serves as a stock gauge for ties 10 which are pushed against flange 13 preliminary to clamping the ties to conveyor bars 27 by cam clamps 28. This operation is performed during an interval of rest of conveyor 1.

Movement of the conveyor following the clamping of tie 10 to the conveyor bar carries the end of the tie through a throat 31 in arm 32 to a position beneath a pin 33 on the arm and above 35 roller 109 on crank 111 of shaft 77, which is journaled in bearing 110 on bed plate 5 and operated in a manner hereafter described.

As is best seen in Figs. 10, 11 and 12, the cam shaft 50 has affixed thereto a plate cam 70 co-operating with a roller 71 on the pin 72 through arms 73 of bell-crank 74, the opposite end of which bears a toothed sector 75. This toothed sector engages gear 76 affixed to shaft 77, which, as viewed in Fig. 12, is rotated in a counter-clockwise direction as roller 71 rides upon the cam surface of increasing radius. The return movement of shaft 77 is effected by the provision of a coil spring 78 surrounding shaft 77 and having one end affixed to the shaft and the other end resting upon bed 5. Increasing tension is placed upon the spring when shaft 77 is rotated by roller 72 riding upon the cam surface of plate cam 70. By virtue of this tension shaft 77 is caused to rotate in such manner that follower 45 72 at all times contacts the surface of cam 70.

55 Gear 90 is also affixed to shaft 77 and drives gear 91 on shaft 92 whereby rotation is imparted to shaft 93 through bevel gears 94, 95. In this manner reciprocatory movement is imparted to 60 crank 96 on shaft 93 for a purpose that will be made apparent.

In a similar manner pinion 101 on shaft 92 drives partial gear 100 to which is affixed a pin 102, which serves a function similar to that of crank 96. The particular construction of gear 100 is such that it permits bale ties from the preceding operation to pass over it preliminary to the forming operation to be produced thereby.

65 A U-shaped support 120 overhangs crank 96 and, in co-operation with anvil 121, forms a throat 122 into which tie 10 is carried by the conveyor 1. A pressure foot 123 overlies anvil 121 and is moved vertically by a rocker arm 124 pivoted at 125 on support 120. The opposite end 70 of rocker arm 124 is provided with a cam roller 75

126 for rolling contact upon the cam surface 127 of plate cam 128 on crank shaft 50.

A yoke 130 is journalled upon cam shaft 50 and has bifurcated ends 131, 132 extending radially therefrom. Guide rod 133 is slidably retained between bifurcations 131, 132 and is moved longitudinally thereof by cylindrical cam roller 134 in cam groove 135 in the face of cam 136 on shaft 50. Pressure foot 123 is affixed to guide rod 133 and hence the horizontal position of the pressure foot is determined by cam 136. Yoke 130 is constantly urged upwardly by compression spring 137 whereby cam roller 126 is constantly maintained in contact with the cam surface of plate cam 128.

15 The construction just described is designed to receive a bale tie in throat 122 after a preceding operation. The bale tie is then clamped upon anvil 121 by actuation of parts through cams 128 and 136. During the clamping period crank 96 is actuated to effect desired forming by bending the tie to form fold 13 as indicated in Fig. 7. This forming operation will be further described in the description of the operation of the machine.

20 A construction similar to that described in connection with Fig. 10 is shown in Fig. 12. This mechanism is designed to perform the succeeding operation. The principal distinction of this construction over that previously described is the provision of a standard 140 in lieu of the U-shaped support of the former construction. The remaining elements are referred to by similar prime numerals.

25 By referring to Figs. 1 and 2, it will be seen that cam shaft 50 extends beyond the rear of the machine and has affixed thereto a gear 148 which meshes with gear 149 on a lower cam shaft 150. This lower cam shaft carries cylindrical cams 162 and 167 which are instrumental in producing desired movement of bell-crank levers 168 and 169 30 pivotally connected to base 5 at 161 and 166, respectively. As is best illustrated in Figs. 4 and 5, the opposite ends of these bell-crank levers extend into the forming throat in which the final wrapping operation for forming the bale tie 35 is performed.

40 Bell lever 162 terminates in the forming throat in an L-shaped figure 163, which lies below the plane of bale tie 10 on conveyor 1. The configuration of the cam slot in cam 167 is such that finger 163 moves to a position immediately beneath tie 10 so that wrapping of the tie metal thereabout will produce the socket opening between the overlapping metal on the longitudinal portion of the tie.

45 Bell lever 167 terminates in the forming throat in a holding plate 168 which normally lies above the plane of the bale tie on conveyor 1. The cam head of cam 162 is of such contour that holding plate 168 moves into co-operative relation with anvil 167 to hold the tie in securely during the 50 wrapping operation.

55 Wrapping of the end 14 of the bale tie to complete the formation of the buckle is effected by roller 170 affixed to crank 169 on shaft 171. This shaft is driven by gear 172 which meshes with teeth on gear 173 on shaft 63. The teeth on gear 173 are disposed in groups each of which engages the teeth of gear 172 at the proper instant to effect a portion of the turns necessary to wrap 60 end 14 around tie 10.

65 In order to produce a buckle that is compact, it is necessary to overcome the resiliency of the metal during the wrapping operation by applying pressure thereto to impart the desired set to the 70 75

wrapped metal. This function is accomplished by the use of pressure feet 200, 201 on opposite sides of the formed buckle. The movements of these pressure feet are controlled in a manner 5 similar to the control of the movements of pressure feet 123 and 123' in the above description. That is, the horizontal positions of these pressure feet are determined by yokes 202, 203, which guide rods 204, 205 to which the pressure feet 10 are attached and which are actuated by cam rollers 206, 207 in cam grooves 220, 221 in the faces of cams 208, 209, respectively. The vertical movement of pressure feet 200, 201 is determined by rocker arms 210 and 211 pivoted at 212, 213, 15 respectively, and having cam rollers 214, 215 which ride upon the cam surfaces of plate cams 216, 217 on cam shafts 50 and 150.

It is to be understood that in the normal operation of the device of the invention a plurality 20 of tie members are passing through the machine simultaneously and that during the interval between indexing operations a buckle forming operation is being performed upon each of the ties successively positioned upon conveyor 1. The 25 following is a description of the operations performed upon a single tie as it progresses through the machine:

Between indexing periods a tie 10 is placed upon the first conveyor bar 27 with the end of the 30 tie overhanging the bar and abutting flange 113 of gauge 112. The tie is clamped in this position by means of cam lever 29 on latching mechanism 28. The next indexing operation moves the tie as indicated by arrow 39, the end of the 35 tie passing through the longitudinal slot in arm 32 to a position under pin 33 and over roller 109 on crank 111. Shaft 77 then makes a half revolution and bends the tie about pin 33 to form fold 11. When this fold is complete crank 111 returns 40 to its original position under the influence of spring 78.

As the material of the tie is relatively resilient it loosely surrounds pin 33 after the tie is released from pressure exerted by roll 109 and the 45 tie can then be moved freely from the pin.

The tie 10 leaves pin 33 during the next indexing operation and moves into throat 122 and under pressure foot 123, which moves downwardly to hold the tie firmly upon anvil 121 through 50 the operation of cam 128 of rocker arm 124. Crank 96 then turns to form fold 13 in the tie over pressure foot 123 whereby end 14 extends at right angles to the remainder of the tie and 14 is guided in this operation by means of guide member 97 depending from support 120. The movement of crank 96 under the influence of plate cam 78 is such that as fold 13 is nearly completed 55 movement of the crank ceases momentarily to allow pressure foot 123 to be withdrawn from the fold through movement of the rocker arm 124 and guide rod 133. As soon as pressure foot 123 is removed from the path of travel of roller 98, crank 96 continues its stroke and returns to its initial position. At the same time pressure foot 60 123 again descends to apply pressure to form a sharp bend at 13.

The succeeding index moves the tie into position for the third operation, which is similar to the second operation except that the metal is 65 folded directly back upon itself as is shown in Figure 8. In order to perform this folding operation, the tie passes over segmented gear 10 and under pressure foot 123', which descends and firmly holds the tie upon anvil 121 while roller 75 102 folds the metal at 16 over foot 123'. After

roller 102 completes its stroke and returns to normal position, pressure foot 123' again descends upon the top of fold 16 to press the metal down, as shown in Figure 8.

The tie with the partially formed buckle is then 5 indexed into position for wrapping the end 14 about the tie. The partially formed buckle passes between blades 163 and 168 of bell crank levers 160 and 165 and pressure foot 201 rests firmly upon blade 163 and the superposed tie 10 while 10 roller 170 begins wrapping end 14 about the overlying folds 19. As crank 169 revolves pressure foot 201 moves from the path of roller 170 by the co-operative operation of guide rod 205 and double internal cam 209. After roller 170 15 makes a complete turn it dwells while upper and lower pressure feet 200 and 201 move against the socket to supply pressure to compact the folds of the metal. Pressure feet 200 and 201 then move from the path of roller 170 to permit the 20 final wrapping of end 14 to take place and to permit roller 170 to return to its original position. Again both pressure feet move into contact with the socket for final pressure. As soon as this pressure is relieved finger 163 and blade 168 25 are withdrawn by means of cams 162 and 167 and respective bell levers 160 and 165. In the succeeding indexing operation lever 29 of cam clamp 28 strikes stop 34 mounted on frame 5, and the integral tie and socket are released to fall from 30 the device upon further indexing movement of the conveyor.

While the foregoing is a description of the specific preferred embodiment of the invention, it is to be understood that various modifications 35 may be made without departing from the spirit of the invention, which is intended to be limited only by the terms of the appended claims as viewed in the light of the prior art.

The invention claimed is:

1. In a machine for forming a combination bale tie and holder from a tie of sheet metal, in combination, means for reversely bending an end of the tie to form an end portion of double thickness, means for folding said end portion across the tie to form a transversely extending portion, means for reversely bending the folded portion upon the tie and means for wrapping the transversely extending portion about the tie to form a socket for receiving the tie end. 40

2. In a machine for forming a combination bale tie and holder from a tie of sheet metal in combination, means for reversely bending an end of the tie upon itself to form an end portion of double thickness, means for folding said end portion across the tie, and means for wrapping the transversely extending portion about the tie to form a loop having the reverse bend underneath the wrapped portion so that expansion of material confined by the tie and holder will press 50 the bend against the wrapped portion. 55

3. In a machine for forming a socket upon a bale tie the combination of tie feeding means, means for reversely bending an end of the tie upon itself to form an end portion of double thickness, means for folding the said end portion across the tie to form a transversely extending loop, means for wrapping the transversely extending loop about the tie to form a socket, and means for indexing said tie feeding means to 65 bring the tie successively into operative relation with the forming means. 70

4. In a machine for forming a combination bale tie and holder from a tie of sheet metal, in combination, means for reversely bending an 75

end portion of the tie to form a length of double thickness, means for folding said end portion across the tie, means for reversely bending the folded portion upon the tie with said end portion extending transversely therefrom, a finger to move into juxtaposition with the tie, and means for wrapping the end portion about the tie and finger to form a socket integral with the tie.

5. In a machine for forming a combination bale tie and holder from a tie of sheet metal, in combination, means for reversely bending an end portion of the tie to form an end portion of double thickness, means for folding said end portion across the tie, a finger to move into juxtaposition with the tie adjacent the fold, means for wrapping said end about the tie and finger, and means for applying pressure to the socket thus formed whereby a compact socket integral with the tie is formed.

10. 6. In a machine for forming a combination bale tie and holder from a tie of sheet metal, in combination, conveyor means, means for securing the tie to said conveyor with the end of the tie to be formed into a holder projecting therefrom, and means for forming the holder on said tie during the movement of said conveyor means.

30. 7. In a machine for forming a combination bale tie and holder from a tie of sheet metal, in combination, conveyor means, means for securing the tie to said conveyor with an end of the tie projecting therefrom, means for forming a holder from the projecting end of the tie during the movement of said conveyor means and means for releasing the tie and holder from the conveyor when the holder is completed.

40. 8. In a machine for forming a combination bale tie and holder from a tie of sheet metal, in combination, means for feeding metal strip to be formed into a bale tie with a holder formed integral therewith, means for folding an end portion of the tie to extend transversely from said strip, and means for wrapping said trans-

versely extending portion about the tie to form a loop for receiving the tie end.

9. In a machine for forming a combination bale tie and holder from a tie of sheet metal, in combination, means for folding an end portion of the tie to extend transversely from the tie, a finger to move into juxtaposition with said tie adjacent the folded end, and means for wrapping said end about the tie and finger to form a socket integral with the tie.

10. 10. In a machine for forming a combination bale tie and holder from a tie of sheet metal, in combination, means for folding an end portion of the tie to extend transversely from the tie, a finger to move into juxtaposition with said tie adjacent the folded end, means for wrapping said end about the tie and finger, and means for applying pressure to the socket thus formed, whereby a compact socket integral with the tie is formed.

15. 11. In a machine for forming a socket upon a bale tie, the combination of tie feeding means, and means for reversely bending an end portion of the tie upon itself to form an end of double thickness.

20. 12. In a machine for forming a socket upon a bale tie, the combination of tie feeding means, means for reversely bending an end portion of the tie upon itself, and a forming mechanism operating at an angle to the tie feeding means for forming a fold in said end portion whereby the end thereof extends transversely of said tie.

25. 13. In a machine for forming a combination bale tie and holder from a tie of sheet metal the combination of, means for folding an end portion of the tie transversely of the tie to form a transversely extending portion, means for reversely bending the folded portion upon the tie and means for wrapping the transversely extending portion about the tie to form a socket 30 for receiving the tie end.

HENRY E. WERNER.
